CLAIM

The ornamental design for a LED luminaire having a mounting system, as shown and described.

DESCRIPTION

FIG. 1 is a front elevational view of the LED luminaire having a mounting system, of the present invention, wherein the elements that are shown in broken lines are disclaimed;

FIG. 2 is a back elevational view thereof;

FIG. 3 is a top, back, left perspective view thereof;

FIG. 4 is a top, back, right perspective view thereof;

FIG. 5 is a left elevational view thereof;

FIG. 6 is a right elevational view thereof;

FIG. 7 is a top plan view thereof; and,

FIG. 8 is a bottom plan view thereof, wherein the elements that are shown in broken lines are disclaimed.

1 Claim, 8 Drawing Sheets
